SUCTION CLEANER

Harry B. White, Canton, Ohio, assignor to The Hoover Company, North Canton, Ohio, a corporation of Ohio

Application October 17, 1941, Serial No. 415,445

3 Claims. (Cl. 15—257)

This invention relates to suction cleaners in general and particularly to cord take-ups for the electric cord which conveys current to the cleaner motor from a source of current.

An object of the invention is to provide a new and improved suction cleaner. Another object is to provide a suction cleaner embodying a cord take-up. A further object is to provide a manually operated cord take-up for winding the cord upon a reel and for unreeling the cord by exerting a pull upon the latter. Other objects and advantages of the invention will be apparent from the following description of the invention shown in the accompanying drawings, wherein:

Figure 1 is an elevational view of an embodiment of the invention;

Figure 2 is an enlarged broken sectional view of the cleaner handle and cord reel operating mechanism;

Figure 3 is a section along the line 3—3 of Figure 2;

Figure 4 is an exploded perspective view of the means for rotating the cord take-up shown in Figures 2 and 3.

The embodiment of the invention herein disclosed comprises a suction cleaner having a cleaner body 65 supported on wheels 66, and pivotally mounted on the body is a handle socket 67 in which is removably carried a handle 70 for moving the cleaner over the surface to be cleaned. A motor housing 68 encloses an unshown motor for rotating a suction creating fan which removes the dirt from the surface being cleaned and discharges it into a bag 69 supported on the cleaner body 65 and the handle 70.

The hollow cleaner handle 70 is provided at its lower end with an electric connector 71 for connection with the plug in the handle socket 67 and at its upper end has a hand grip 72 which supports a switch 73. Attached to the bottom wall 74 of the cleaner handle is a cord reel casing 75 split vertically to be formed of two complementary casing sections secured together by screws 76 and has a circular portion 77 for a reel 78 and a reduced neck portion 79 through which the cord 27 passes. Secured to the bottom handle wall 74 and extending from the neck 79 to the hand grip 72 is a cord housing 80 for the cord 27.

A plate 81 is secured by screws 82 to the bottom wall of the cleaner handle and has a boss 83 for rotatably supporting a reel shaft 84 which is held against axial movement by a ring 85 attached to the shaft 84 and abutting the boss 83. The reel 78 has a central boss 86 rigidly at-

tached to the shaft 84 by a set screw 87 and is provided with a drum 88 and spaced flanges 89, 89 for receiving the cord 27. Attached to the central boss 86 by screws 90 is an insulating block 91 on which is mounted a pair of leaf spring contacts 92, only one of which is shown, and connected thereto are the fixed terminal ends of the cord 27. Rigidly attached to the plate 81 is an insulating ring 93 provided with annular collector rings 94 which engage the contacts 92. A lead 95 is connected to one of the collector rings 94 and extends downwardly in the hollow handle 70 to the electric plug 71 and extending upwardly therefrom in the handle 70 is a lead 96 connected to the switch 73 from which extends a lead 97 connected to the other collector ring 94 to complete the motor circuit.

In order to rotate the reel 78 a positioning gear 106 is journaled on the reel shaft 84 for engagement with a spring pressed pawl 107 mounted on the supporting plate 81 attached to the cleaner handle 70. The gear 106 is provided with two lugs 108 which project through holes 109 in the pinion 110 for securing the latter to the gear 106. Mounted on the pinion 110 is a spring pressed pawl 111 which engages a ratchet wheel 112 rigidly secured to the reel shaft 84. An elongated slide rack 113 is slidably mounted in the handle 70 by brackets 114 and has a finger grip 115 extending through a slot 116 in the side wall 117 of the handle at the upper end thereof. The lower end of the slide rack 113 is provided with teeth 118 which engage the gear 110 for coiling the cord 27 on the reel. The teeth 118 are normally held out of engagement with the gear 110 by means of a spring 119 attached to the slide rack 113 and to the bottom wall of the cleaner handle 70.

In operation, if it is desired to uncoil the cord 27, the operator pulls the cord through the cord housing 80 and causes the reel to rotate freely without movement of the slide rack 113, since the spring 119 functions to hold the teeth 118 out of engagement with the gear 110. When it is desired to wind the cord on the reel 78, the operator grasps the finger grip 115 and moves the slide rack 113 upwardly in the handle whereby the teeth 118 engage the gear 110 to rotate the latter about the reel shaft 84, such rotation causes the pawl 111 to engage the ratchet wheel 112 and thus rotates the shaft 84 and the reel 78 to coil the cord on the reel. Upon the down stroke of the slide rack 113, the gears 106 and 110 are rotated in the opposite direction since the pawls 107 and 111 slip along the gear 106.

and the ratchet 112, respectively, without rotating the reel 78, and upon continued reciprocation of the slide rack 113, the cord is wound about the reel 78. The pawl 107 at all times engages the gear 106 and permits rotation of the latter in opposite directions to maintain the gear 106 in proper position for re-engagement with the teeth 118 upon the up stroke of the slide rack 113.

I claim:

1. In a suction cleaner, a cleaner body, a handle on said body, a motor, a cord reel mounted on said handle at the lower end thereof, a cord on said reel and connected to said motor and having a free end for connection to a source of current, hand operated reciprocating means slidably mounted on said handle and connected to said reel for rotating the latter to coil said cord thereon upon reciprocating said means, and means urging said reciprocating means out of engagement with said reel to permit unwinding said cord by exerting a pull thereon.

2. In a suction cleaner, a cleaner body, a handle on said body, a motor, a cord reel mounted

on said handle at the lower end thereof, a cord on said reel and connected to said motor and having a free end for connection to a source of current, hand operated reciprocating means 5 slidably mounted on said handle and connected to said reel for rotating the latter to coil said cord thereon upon reciprocating said means, means urging said reciprocating means out of engagement with said reel to permit unwinding 10 said cord by exerting a pull thereon, and means for positioning said reel for proper re-engagement with said reciprocating mean upon operation of said reciprocating means to wind the cord on said reel.

15 3. A cord take-up comprising, a cord reel, a cord on said reel, reciprocating means connected to said reel for rotating the latter to coil the cord thereon, and means urging said reciprocating means out of engagement with said reel to 20 permit unwinding of said cord by exerting a pull thereon without movement of said reciprocating means.

HARRY B. WHITE.
